TAPE CARTRIDGE OR SIMILAR ARTICLE

John O. Fundingsland, El Paso County, Colo.
(1126 N. Sheridan, Colorado Springs, Colo.)

Filed Oct. 19, 1964, Ser. No. 82,219

Term of patent 14 years

(Cl. D26—14)

Fig. 1
Fig. 2

Fig. 3

Fig. 4

The ornamental design for a tape cartridge or similar article, as shown and described.
